INVENTOR
ELIZABETH M. COOK

BY Chas. E. Lourmead
ATTY.

UNITED STATES PATENT OFFICE.

ELIZABETH M. COOK, OF BELVEDERE, CALIFORNIA.

DESIGN FOR A CHILD'S OUTER GARMENT, SUCH AS A PLAY-SUIT.

59,540.

Specification for Design.

Patented Nov. 1, 1921.

Application filed June 22, 1921. Serial No. 479,661. Term of patent 3½ years.

To all whom it may concern:

Be it known that I, ELIZABETH M. COOK, a citizen of the United States, residing in Belvedere, county of Marin, State of California, have invented a new, original, and ornamental Design for a Child's Outer Garment, Such as a Play-Suit, of which the following is a specification, reference being had to the accompanying drawing, forming part thereof.

Fig. 2 is a view in rear elevation of a child's garment showing my design.

I claim:

The ornamental design for a child's outer garment, such as a play-suit, as shown.

ELIZABETH M. COOK.
